UNITED STATES PATENT OFFICE.

SIDNEY JAMES SANFORD, OF BARRIE, ONTARIO, CANADA.

FIRE-TELEGRAPHY.

SPECIFICATION forming part of Letters Patent No. 337,439, dated March 9, 1886.

Application filed September 1, 1884. Serial No. 111,976. (No model.)

To all whom it may concern:

Be it known that I, SIDNEY JAMES SANFORD, of the town of Barrie, in the county of Simcoe, in the Province of Ontario, Canada, 5 accountant, have invented certain new and useful Improvements in Fire-Telegraphy, of which the following is a specification.

The invention relates to that class of telegraph fire-alarms in which the bell at a fire-station is caused to indicate by strokes the particular number represented by the street-box from which the alarm is given; and the object of the invention is to so arrange the apparatus that a single street-circuit may be 15 utilized for the purpose of operating certain mechanism, by which a number representing the particular box from which the alarm is given is posted in the fire-hall simultaneously with the ringing of the bell; and it consists, 20 essentially, first, in peculiarly-arranged mechanism in the street-box, by which the street-current is first broken, so as to actuate the numbering mechanism within the fire-hall, and afterward to actuate the mechanism within 25 the fire-hall by which the bell is caused to strike.

In the drawings, Figure 1 is a perspective top view of the numbering apparatus. Fig. 2 is a perspective top view of the numbering 30 apparatus with the top plate removed. Figs. 3 and 4 are perspective views of the operating mechanism of the street-box. Fig. 5 is a perspective view showing the general arrangement of the wires.

35 In the drawings like letters of reference indicate corresponding parts in each figure, which figures I have arranged in general to indicate the street-box and its connection by a single street-circuit to the fire-alarm and numbering mechanism, and in detail to indicate the component parts of the mechanism involved in the invention.

40 A represents one end of the street-wire, which is connected to the body or frame of the street box mechanism. B is the other end of the street-wire, which is connected to the contact-spring C. The other end of this contact-spring rests on the center portion of the wheel D. This wheel is fixed to the spindle E, but 45 is insulated from it. On each side of the contact-spring C the wheel D has fitted in its per-

ipheries rubber or other insulating material, the said rubber or other insulating material being divided and set in the periphery, so that on one side of the contact-point of the spring 55 C the periphery of the wheel shall be brass, while on the other side of the contact-point the periphery of the wheel shall be insulating material, so that the current conveyed into the wheel D by the contact-spring C cannot escape through the contact-spring F during the period that it is intended that it should pass from the contact-spring G. The contact-spring G is connected by the wire H to the contact-spring I, which is arranged to come in contact with the periphery of the wheel J. This wheel is fixed to its spindle K, and is not insulated from the said spindle, so that any current conveyed into the wheel J shall pass through the frame L back into the street-wire A. The periphery of the wheel J has a number of non-conducting spaces, a, made in it so that the current shall be broken at intervals as the surface of the wheel J is carried past the contact-point of the spring I. These 65 non-conducting spaces are arranged to correspond in number with the number represented by the street-box, or, rather, are arranged so as to break the current the number of times necessary to operate the numbering mechanism in the fire-hall, as hereinafter more particularly explained. The contact spring F is connected by the wire M to the contact-spring N. The end of this contact-spring N is arranged to come into contact with the wheel O, 70 which has a number of non-conducting spaces, b, arranged in its periphery to correspond with the number of the box to be indicated by the bell in the hall.

75 As before stated, when the current is arranged to pass into the frame L through the contact-spring G, the contact-spring F is held out of circuit by resting on the non-conducting material in the wheel D, and vice versa when the current is conveyed into the frame 80 L through the contact-spring F the contact-spring G is then held out of circuit by the non-conducting material on the wheel D. In this way the wheel O is out of circuit when the wheel J is operating the numbering mechanism, while when the wheel O is operating the bell-circuit the wheel J is held out of circuit.

cuit. Thus the same circuit is utilized for the purpose of performing two distinct services over the same street-wire.

As I claim nothing peculiar in the plan for driving the mechanism in the street-box, it is not necessary to describe or show it in detail. It is sufficient to merely say that the gearing is driven by any kind of mechanism adopted in street-boxes used in fire-alarm telegraphy.

The only points to be observed are, first, that the spindle *E* on which the wheel *D* is fixed shall be so geared to the spindle *K* on which the wheel *J* is fixed that the said wheel *J* shall make one revolution while the wheel *D* merely moves sufficiently to bring the contact-point of the spring *G* from one end of the conducting-space *a* to its other end, so that the wheel *D* shall be in contact through the contact-spring *G* only during the period that the wheel *J* revolves; and, secondly, that the wheel *O* shall be so geared relatively that the wheel *D* with it shall revolve three times during the period that the wheel *D* moves sufficiently to bring the contact-point of the spring *F* from the commencement to the end of the conducting-surface. The wheels *J* and *O* are geared in this manner so that the numbering apparatus shall only be moved to indicate once the given number of the box, while the wheel *O* revolves three times in order to cause the striking mechanism to operate so as to give the alarm of the box three times in succession.

The foregoing will be sufficient to indicate the changes in the street-box which will be necessary to operate my invention, so far as it may be affected by the street-box.

The next point is to describe the mechanism by which the numbering apparatus and bell-circuit are operated by the current from the street-wire. Street-wire *A*, *B* is connected to the binding-post *P*. These binding-posts are insulated from the frame *Q* of the machine, but are connected to the helix of the electro-magnets *R*, so that the current in passing from *A*, *B* passes through the electro-magnets *R*, keeping them charged during the period that the circuit is closed.

S represents wires leading from an independent battery and connecting a bell-working apparatus. One of the wires is connected to the binding-post *T*, which is insulated from the frame *Q*. The other wire is connected to the binding-post *U*, which is not insulated from the frame *Q*.

V is a wire leading from the binding-post *T* to the core *W'* of the electro-magnet *R*. So long as the lever *X* is in contact with the core *W'* the circuit from the wires *S* is complete through the frame *Q*, as the lever *X* is connected to the said frame by its pivoted spindle *Y*.

Z is a spring designed to throw the lever *X* away from the core *W'*. (See Fig. 2.) From this it will be seen that so long as the street-wire *A*, *B* is in circuit the lever *X* will be held in contact with the core *W'*, and conse-

quently the bell-circuit will be closed. The instant that the street-circuit is broken the spring *Z* will draw the lever *X* away from the core *W'*, thereby breaking the bell-circuit. When the street-circuit is closed again the power of the magnet is sufficient to draw the lever *X* back again against the core *W'*, thus closing the bell-circuit. Consequently each time that the street-circuit is opened and closed the lever *X* leaves and returns to the core *W'*, and through its motion the entire mechanism of the number-indicating apparatus and the bell-ringing apparatus is controlled.

c (see Fig. 2) is a spindle journaled in the frame *Q* and caused to revolve by the action of the spring *d*.

e is a spur-wheel fastened to the spindle *c*, and arranged to mesh with the pinion *f*, fastened to the spindle *g*. To this spindle *g* is also keyed the spur-wheel *h*, which meshes with the pinion *i*, fastened to the spindle *j*. The spur-wheel *k* is fastened to the spindle *j* and meshes with a pinion, *m*, which is keyed to the spindle *n*, on which is fastened what may be termed a "fly-stop," *o*, which fly-stop is therefore caused to revolve by the action of the spring *d*, but so long as the lever *X* is held against the core *W'*, the forked end of the lever *X* pressing against the fly-stop *o*, and by holding it stationary prevents the chain of mechanism leading from it to the spring from moving. Each time that the circuit is broken by the lever *X* moving on its pivot *Y* and leaving the core, the fly-stop *o* is permitted to make one-half a revolution, and when the circuit is closed by the lever *X* coming in contact with the core the balance of the revolution is made by the fly-stop *o*, so that in proportion to the number of times that the current is opened and closed the fly-stop *o* will revolve and the chain of mechanism leading from the fly-stop *o* to the spring *d* will move.

p (see Fig. 1) is a spur-wheel keyed to the top of the spindle *g*. Consequently the spur-wheel *p* will be caused to revolve in proportion to the number of times that the circuit is opened and closed. This spur-wheel *p* is arranged to operate the numbering mechanism, as hereinafter explained.

r is a spring arranged to impart motion to the spur-wheel *s*, which is keyed to the same spindle as the spring *r* is fastened to. This spur-wheel *s* meshes with the pinion *t*, fastened to the spindle *u*, on which spindle is fastened the spur-wheel *v*, arranged to mesh with the pinion *w*, which is keyed to the same spindle as the spur-wheel *x*. This latter spur-wheel meshes with the pinion *y*, which is fastened to the same spindle as the escapement-wheel *z*. It will be seen from this description that the chain of gearing between the spring *r* and escapement-wheel *z* will be driven by the action of the spring *r*, which action is, however, to a certain extent controlled by the hooked end of the lever *X*, which is arranged to engage with the teeth of the escapement-wheel *z*, and intermittently arrest its motion during

the period that the circuit is being opened and closed.

In order to hold the chain of gearing operated by the spring *r*, I fix to the spindle *u* a 5 notched wheel or cam, 2, and provide a lever, 3, which is pivoted on the frame *Q*, as at 3', and has a hooked end arranged to engage with the notched wheel 2. The other end of the lever 3 is held by the spring 4, so as to keep 10 the hooked end of the lever 3 in contact with the notched wheel 2.

5 is a pinion fixed to the spindle *j*, and bearing against the lever 3, so that each tooth as it comes around will move the lever and cause 15 it to come out of the notches of the cam 2. The spindle *j* is so geared to the fly-stop *o* that for each half-revolution of *o* one tooth of the pinion 5 will work against the lever 3 and push it out of the notch it may happen to be in.

20 6 is a hooked catch.

7 is a spring which keeps the hooked catch 6 continually pressing against the end of the lever 3, so as to engage with the lever 3 whenever it is pressed out of a notch of the cam 2, 25 and to hold the lever 3 until such time as a notch in the cam 2 comes round to the catch 6 and moves it away from the lever 3, and thus releases it.

8 is a cam fixed to the spindle *u*.

30 9, 10, and 11 are levers carrying at one end the pinions 12, 13, and 14, respectively, and provided with springs at the other end which keep them continually pressed against the cam 8, and are so arranged that the cam 8, 35 when made to revolve, presses against them so as to put the pinions 12, 13, and 14 into and out of gear with the spur-wheel *p* alternately. The cam 2 has four notches, three of such a size that the lever 3, when pressed out by the motion 40 of the pinion 5, releases the cam 2. The fourth is so much larger that the lever 3, when pressed out by the pinion 5, does not move sufficiently to release the cam 2, and thus the motion of this chain of gearing is stopped

45 whenever the lever 3 engages with this fourth notch until such time as the lever 3 is pressed out by hand. The notched wheel 2 and the cam 8 are fixed to the spindle *u* in such a manner that when the lever 3 is in the largest notch 50 the cam 8 will be in such position that the pinions 12, 13, and 14 will all be out of gear with the spur-wheel *p*, (see Fig. 1,) and, if the lever 3 be pushed out by hand, so as to release the cam 2, and the spindle *u* is allowed to re-

55 volve until stopped by the lever 3, catching in the next notch of the cam 8, the cam 2 will then have turned so as to press against the lever 9 and move the pinion 12 into gear with the spur-wheel *p*, and when the cam 2 is 60 released by the lever 3, being pushed out by the pinion 5, and is allowed to revolve until again caught by the lever 3 coming to the next notch, the cam 8 will have revolved, so as to let the pinion 12 out of gear, and the pinion 13 will be moved into gear with the upper 65 wheel, *p*, and the cam 2 being released and caught in the next notch the cam 8 will have

moved so as to press against the lever 11 and move the pinion 14 into gear with the spur-wheel *p*.

70

15 is a lever pivoted in the frame *Q*.

16 is a spring which draws one end of the lever 15 against the lower end of the insulated binding-post *T*.

17 is a cam fixed in the spindle *u*, and made 75 to come against the lever 15, so as to move it away from contact with the binding-post *T*. Now, as the lever 15 is not insulated from the frame *Q*, whenever it is in contact with the binding-post *T* the circuit from the wires *S* is 80 complete and the action of the lever *X*, which is controlled by the electro-magnets *R*, will have no influence on the bell-circuit *S*, so that, in fact, the bell-circuit *S* will be cut off from control of the street-circuit *A B*. The cam 17 is 85 so fixed in the spindle *u* that when the machine is at rest the lever 15 will be pressed away from the binding-post *T*, so that the circuit from the wires *S* will be broken there, but completed through the lever *X* and the core *W'*, 90 and the first break of the street-circuit will allow the lever *X* to move away from the core *W'*, and thus break the bell-circuit *S*. As soon as this action has taken place, the cam 17 will have revolved past the end of the lever 15, 95 and the spring 16 will draw the lever 15 against the binding-post *T*, where it will remain until the numbering apparatus has indicated the box struck. The cam 17 will then have revolved around so as to press against the lever 100 15 and again move it away from the binding-post *T*, thus allowing the bell-circuit *S* to be operated by the street-circuit *A B*.

The pinions 12, 13, and 14 carry numbering disks, which are each numbered from 0 to 105 9. One digit of each disk is seen through a slot in the outside cover of the machine. When the machine is at rest, the 0 will show and the pinion 12 will be in gear with the spur-wheel *p*.

110

I will now describe the action. When the street box is at rest, the contact-spring *G* will be bearing on a conducting-space, and the contact-spring *F* will be bearing on a non-conducting space, so that the street-circuit *A B* 115 will be complete through the contact-spring *I* bearing on the wheel *J*. The non-conducting spaces on the periphery of the wheel *J* are arranged in three groups. The first group represents the hundreds, the second group the 120 tens, and the third the units, and in the numbering apparatus the disks each correspond to one of these groups, so that whatever number is required for the hundreds-disk there will be that number of non-conducting spaces in the 125 hundreds group of the wheel *J*, and so with the tens and units. The street-box being put in motion the contact-spring *I* comes on a non-conducting space, and thus breaking the circuit it will cause the electro-magnets *R* in the 130 numbering apparatus (see Fig. 1) to release the lever *X*, and this will allow the fly-stop *o* to make half a revolution. At the same time this will break the bell-circuit *S*, and cause

the bell to give one stroke, and the pinion 12, being in gear with the spur-wheel p , will be moved from the figure 0 to the figure 1. When the contact-spring I comes on the next conducting-space, the lever X will be drawn against the core W' and will allow the fly-stop o to complete its revolution. The pinion 12 will have turned to the figure 1 and the lever 3 will have been pushed out by the pinion 5, so as to release the cam 2. This will allow the spindle u to turn slightly, and the cam 17 will move away from the lever 15 and allow it to come in contact with the binding-post T, thus cutting off the bell-circuit S, as before described, and for every time the contact-spring I passes over a non-conducting space on the wheel J, the pinion 12 will be turned so as to show a different number until all of the hundreds group have been passed. During this time the intermittent action of the escapement-wheel Z, by acting intermittently on the lever X, prevents the chain of mechanism from moving rapidly; but when the contact-spring I has passed over the first group of figures it comes to a long conducting-space, when the lever X, being held in contact with the core W', the escapement-wheel z will turn rapidly until the cam 2 is caught in the next notch by the lever 3. This action will turn the cam 8, so as to release the lever 9 and come against the lever 10, thus causing the pinion 12 to be out of gear and putting the pinion 13 into gear. When the contact-spring I comes to and passes over the second group on the wheel J, the same action will take place in the numbering apparatus, only the second or tens disk will be turned to its number, and the lever 15 will still remain in contact with the binding-post T, and so with the third group and units-disk. When the third long conducting-space on the wheel J has been reached by the contact-spring I, cam 8 will come around, so that all the pinions 12, 13, and 14 will be out of gear. Cam 17 will have come around and pressed against the lever 15, and move it away from the binding-post T, and the cam 2 will have come around until caught by the lever 3 in the long notch, and, as before described, this will arrest the motion of the chain of mechanism until the lever 3 has been released by hand. The figures representing the number of the street-box will then show through the slot in the face of the numbering apparatus. The wheel J in the street-box having now made one revolution, the contact-spring G passes onto a non-conducting space on the wheel D, and the contact-spring F passes onto a conducting-space, thus transferring the current from the wheel J to the wheel O through the contact-spring N, when the wheel O, revolving, brings the contact-spring N over a non-conducting-space and thus breaks the current, causing the electro-

magnet R in the numbering apparatus to release the lever X, and as the lever 15 is not now in contact with the binding-post T, this action will break the bell-circuit S between the armature W and the lever X and thus cause the bell-striking apparatus to give one stroke, and as the contact-spring N passes over each non-conducting space on the wheel O one stroke of the bell will be given in like manner until the proper number has been struck.

What I claim as my invention is—

75

1. In fire-alarm telegraphy, a street-alarm box provided with circuit-closing springs F and G, rotating wheel D, arranged to bring said springs alternately into circuit, two circuit-breakers, as J O and I N, and line-connections, substantially as described, combined with a numbering apparatus provided with the electro-magnet R R, lever X, fly-stop o, and escapement z, intermittently released by said lever to control the numbering-disks, substantially as described.

80

2. In a device for the purpose described, the combination, with the numbering-disks p, 12, 13, and 14, and levers and cams, as described, of the escapement z, spring r, chain of gearing arranged between said escapement and spring and driven by said spring, the electro-magnet R R, fly-stop o, and lever X, intermittently attached thereby to control said chain of gearing and numbering-disks, as set forth.

90

3. In fire-alarm telegraphy in which a numbering apparatus, as p, 12 13 14, and connections to exhibit the number of the alarm struck is employed in addition to the alarm-bell mechanism, as described, arranged to operate the numbering apparatus, and controlled through breakers I N J O and connections by a single street-circuit, in combination with bell-operating mechanism provided with an independent circuit, S, connected to the numbering apparatus and controlled by the action of the mechanism of the numbering apparatus, substantially as herein specified.

100

4. In fire-alarm telegraphy in which a numbering apparatus, as p, 12 13 14, and connections to exhibit the number of the alarm struck is employed in addition to the alarm-bell mechanism, as D J O, and springs F G I N, operated from a single street-circuit and connected to an independent bell-circuit, S, a fly-stop, o, and lever X, all arranged and operated to first strike the bell once, then set the indicating-numbers, and finally strike the alarm on the bell, substantially as set forth.
